B. L. HANSON

AUTOMATIC DRIFTING DEVICE FOR LOCOMOTIVES

Filed April 23, 1920

UNITED STATES PATENT OFFICE.

BYRON L. HANSON, OF CHICAGO, ILLINOIS.

AUTOMATIC DRIFTING DEVICE FOR LOCOMOTIVES.

Application filed April 23, 1920. Serial No. 376,065.

To all whom it may concern:

Be it known that I, BYRON L. HANSON, a citizen of the United States, and a resident of Chicago, in the county of Cook and State 5 of Illinois, have invented a new and useful Improvement in Automatic Drifting Devices for Locomotives, of which the following is a full, clear, and exact description.

My invention relates to improvements in 10 automatic drifting devices for locomotives, and it consists in the combinations, constructions, and arrangements herein described and claimed.

An object of my invention is to provide 15 a drifting device for a locomotive which will be automatically operated when the throttle of the locomotive engine has been closed while the locomotive is in motion, thereby permitting a flow of dry steam 20 through the engine valve chamber and cylinder, thus preventing cinders, soot, and the like from being deposited in the valve chamber and cylinder and providing a cushion of steam therein.

25 A further object of my invention is to provide a device of the type described that automatically becomes inoperative when the throttle of the engine is opened or the locomotive is stopped.

30 A further object of my invention is to provide a device of the type described that can be readily applied to a locomotive engine of an ordinary construction.

35 A further object of my invention is to provide a device of the type described that is relatively simple in construction and operation, and which is not likely to get out of order easily.

40 Other objects and advantages will appear in the following specification, and the novel features of the invention will be particularly pointed out in the appended claims.

45 My invention is illustrated in the accompanying drawings, forming part of this application, in which—

Fig. 1 is a diagrammatic view of a portion of a locomotive engine to which the device has been applied, the device being shown in side elevation, portions being broken away and other portions being shown in section.

50 Fig. 2 is a central longitudinal sectional view of an enlarged portion of the device,

55 Fig. 3 is an orthographic projection along the line 3—3 of Fig. 2,

Fig. 4 is a detailed view of a portion of the device.

In carrying out my invention, I make use of a locomotive engine 1 provided with a cylinder 2 having a valve chest 3 mounted 60 thereon. Steam is admitted to the valve chest 3 in an ordinary manner, no means therefor being shown in the accompanying drawings, and is distributed to the cylinder 2 through the ports 4 and 5. Piston valves 65 6 and 7, which are rigidly secured to the piston valve rod 8 and which are reciprocated in the valve chest 3 to control the distribution of steam to the cylinder 2, are provided with piston rings 12 and 13. A piston 9, 70 provided with a piston ring 11, is rigidly secured to the piston rod 10 and is reciprocated within the cylinder 2 by the action of the steam which has been admitted through 75 the ports 4 and 5.

The parts described so far are of ordinary construction and form no part of my invention except in so far as they cooperate with the parts to be hereinafter described. The operation of the parts already described 80 is well known in the art. The exhaust steam from the cylinder is conducted in any ordinary manner to the smoke box (not shown) of an engine and is allowed to escape up the smoke stack. Consequently 85 when the throttle is closed and the engine is in motion, cinders, dust, soot, and the like will be drawn into the valve chest and the cylinder, forming a deposit therein and interfering seriously with the operation of 90 the piston 9 and the piston valves 6 and 7.

I provide a casing 14 having ends 19 and 20. The casing 14 is best seen in Fig. 2 of the accompanying drawings and is mounted upon the valve chest 3, being maintained 95 thereon by any suitable fastening means, none being shown in the accompanying drawings. A partition 15 is disposed within the casing 14 and may be formed integrally with the walls of the casing. An air chamber 16 and a vertical chamber 17 are thus provided. The vertical chamber 17 has its lower end open and in registration with an opening 18, which is formed in the wall of the valve chest 3, thereby permitting the 105 live steam to flow into an enlarged portion 21 of the vertical chamber 17. The pressure of the steam tends to maintain the piston valve 22 against a valve seat 22'. A piston 23 is disposed in the upper end 110

of the vertical chamber 17 and is rigidly secured to a rod 24 in any suitable manner, as by means of a nut 25, which is screwed on the end of the rod 24. The other end 5 of the rod 24 is connected at 26 by a swivel joint with an end of a second rod 27, which is rigidly secured to the piston valve 22 by means of a nut 28, thereby rigidly connecting the piston valve 22 with the piston 23 10 in such a manner as to permit a rotatable movement of the piston valve 22. It will be noted that the rod 24 extends through the opening 29 in a horizontal partition 30, which is formed integrally with the walls 15 of the chamber 17 or may be secured therein in any suitable manner. A pin 31 is inserted transversely through the rod 24 and a spring 32 is disposed between the projecting ends of the pin 31 and the partition 30, 20 thereby tending to maintain the piston valve 22 against the valve seat 22'.

A substantially rectangular frame-like extension 33 is formed integrally with the partition 15 to project within the air chamber 16. It is obvious that the frame-like extension 33 could be formed separately and rigidly secured to the partition 15 by any suitable fastening means. A valve plate 34 is disposed within the rectangular frame-like extension 33 and is maintained therein by a spring member 37, which is secured at its middle to the valve plate 34 by means of a bolt 38 and has its ends arranged to press against the inner surface of a bar 35, 25 which is secured at 36 to the frame-like extension 33. The valve plate 34 is formed with a recess 41 in its inner surface and also with a U-shaped groove 42 located above the recess 41. The partition 15 has a slot 39 formed therethrough which is greater in extent than the recess 41. A pin 40 has one end rigidly connected with the rod 24 and is arranged to extend at right angles thereto in such a manner that its other end 45 extends through the slot 39 and is received within the recess 41. An air passage 43 in the partition 15 communicates at one end with the U-shaped groove 42 when the valve plate 34 is in the position pictured in Fig. 2 of the accompanying drawings extends through the casing 14. A second air passage 44 is positioned with respect to the air passage 43 so that it communicates with the other end of the U-shaped groove 42 when the passage 43 is in communication with the latter. The passage 44 opens into the chamber 17 between the piston 23 and the adjacent wall of the casing 14.

The air chamber 17 is also provided with 60 an air outlet 45 which is positioned between the piston 23 and the adjacent wall of the casing 14. The outlet pipe 45 extends to a casing 46, (see Fig. 1) which is secured to a portion of the locomotive engine by means 65 of a bracket 47, or in any other suitable

manner. A piston 60 is disposed within the casing 46 and is maintained in the position pictured in Fig. 1 by means of a spring 49 which is arranged about a stem 48. The end of the stem 48 is pivotally connected at 70 52 to a lever 50 which is fulcrumed at 51. The other end of the lever 50 is pivotally connected at 53 to a stem 54 which extends within a steam chamber 55 and is rigidly connected to a valve 61 which is disposed therein. This valve controls the flow of live steam through the pipe 57. The live steam passes through a pipe 56 into the steam chamber 55. The pipe 56 is connected to a source of steam supply (not shown) which is provided in a locomotive engine of an ordinary construction. It is to be noted that the pipe 57 communicates at 58 with the valve chest 3.

From the foregoing description of the 85 various parts of the device, the operation thereof may be readily understood. While the throttle remains open and the piston valves 6 and 7 and the piston 9 are being reciprocated in an ordinary manner by the 90 pressure of live steam, the piston valve 22 will be maintained in the position shown in Fig. 2. Consequently the other portions of the device shown in Fig. 2 will remain in the positions pictured therein. When the 95 throttle is closed while the locomotive is in motion, as when coasting down grade, the live steam will no longer pass into the valve chest 3, although the valve pistons 6 and 7 and the piston 9 will be reciprocated so 100 long as the locomotive is in motion. The live steam within the valve chest 3 and the cylinder 2 will be drawn therefrom in the exhaust. The suction created by the draft 105 will overcome the tension of the spring 32, thereby causing the piston 22 to move downwardly. It will be noted that the pin 40 can be moved downwardly a spaced distance before the valve plate 34 will be moved.

When, however, the pin 40 has been moved 110 downwardly beyond that distance, the valve plate 34 will also be moved, thereby permitting the flow of compressed air through the air passage 44 into the space between the piston 23 and the wall of the casing 14. It 115 is to be noted that the air inlet pipe 59 communicating with the air chamber 14 extends to an air reservoir (not shown) that is ordinarily provided in a locomotive steam engine and that the air chamber 14 is in fact 120 an auxiliary reservoir for air under pressure. The pressure of the air against the piston 23 will tend to hold the same in its downward position when the live steam has all been driven from the valve chest 3 and the cylinder 2. Otherwise, since there would 125 no longer be a suction to maintain the valve piston 22 in its downward position, the latter would be moved against its seat by 130 the tension of the spring 32.

The air from the air chamber 16, which has passed into the upper end of the chamber 17, passes through the pipe 45 into the casing 46 and operates the piston 60 against the tension of the spring 49. The lever 50 operates the valve 61 in the steam chamber 55, thereby permitting the passage of dry steam through the steam pipe 57 into the valve chest 3. Dry steam passing therein will drive cinders, soot, and the like, from the valve chest 3 and from the cylinder 2. The dry steam also passes into the enlarged portion 21 of the chamber 17 and presses against the piston valve 22. When the upward pressure of the dry steam against the piston valve 22 overcomes the downward air pressure against the piston 23, the piston valve 22 will be moved upwardly against its seat 22', thereby moving the valve plate 34 upwardly. The U-shaped groove 42 will then communicate with the air passages 43 and 44, as pictured in the accompanying drawings. Air can no longer flow from the air chamber 16 to the chamber 17. Any steam which has penetrated within the chamber 17 as well as the compressed air in that chamber escapes through the air passage 44, the groove 42, and the passage 43, since the latter extends through the casing 14. A sufficient quantity of dry steam will remain within the valve chest 3 and the cylinder 2 to provide a cushion for the pistons when the throttle is again opened.

All cinders, soot, dust, and the like, are driven from the valve chest 3 and the cylinder 2 and cannot form a coating for the piston as would otherwise be the case.

It is obvious that many modifications and adaptations of the form of the device illustrated in the accompanying drawings may be provided without departing from the spirit and scope of my invention as set forth in the foregoing disclosure and outlined more particularly in the appended claims. I therefore consider such modifications and adaptations as my own.

In service, a check valve 62 would be provided in the pipe 57 to prevent the passage of steam from the valve chest 3 to the steam chest 55. Likewise, a cock 63 or the like would be disposed in the pipe 57 to control the passage of steam therethrough.

I claim:

1. In a reciprocating steam engine provided with the usual steam chest, the combination of an auxiliary steam supply line leading to the steam chest, a valve interposed in the steam supply line, a casing supported adjacent to the valve chest and divided by a transverse partition into a reservoir for a pressure fluid and a valve chamber communicating at one end with the steam chest, said valve chamber being divided by a transverse partition into two compartments and said first named partition

being formed with a passage therethrough leading from the storage reservoir to the compartment of the valve chamber remote from the steam chest, a valve controlling the passage of a pressure fluid from the storage reservoir into the upper compartment of the valve chamber, a differential piston valve operatively connected with the last named valve, and means arranged between the valve in the steam supply line and the compartment of the valve chamber remote from the steam chest for controlling the operation of the former, said last named means being arranged to be actuated by the pressure fluid passing through the said compartment at times to occasion the opening of the valve in the steam supply line.

2. The combination with the steam chest of a locomotive engine, of a casing supported adjacent to the steam chest, said casing being divided by a vertical partition into a reservoir for a compressed fluid, and a valve chamber, said valve chamber being divided by a horizontal partition into an upper compartment and a lower compartment, said lower compartment being arranged to communicate with said steam chest, said vertical partition being formed with a passage therethrough leading from the reservoir to the upper compartment of the valve chamber, with a second passage communicating at one end with the valve chamber and being open at its other end to the atmosphere, and with a vertical slot therethrough positioned adjacent to the said passages, a valve plate maintained in slidable contact with the first named partition and formed with a groove in its inner face adapted to communicate at times with the first and second named passages through the vertical partition, a piston valve normally seated in the lower compartment of the valve chamber, a piston reciprocatively disposed in the upper compartment, a stem slidably received in an opening in said horizontal partition and connecting the piston and the piston valve, a laterally extending pin carried by said stem and projected through said slot in the wall of the vertical partition for engaging with said slidable valve plate to move the latter into open position when said piston valve is moved a predetermined distance from its seat, and a delivery conduit communicatively connecting with said upper compartment above the piston disposed therein.

3. The combination with the steam chest of a locomotive engine, of a casing supported thereon and divided by a vertical partition into a reservoir for a pressure fluid, and a valve chamber, said valve chamber being arranged in open communication at its lower end with the steam chest and being divided by a horizontal partition into an upper compartment and a lower compartment.

ment, said upper compartment being provided with an outlet orifice adjacent to its upper end, said vertical partition being formed with a passage leading from the reservoir to the upper compartment and communicating with the latter at a point adjacent to its upper end, a slideable valve plate normally maintained in position to close said passage, a piston arranged for reciprocation in the upper compartment below the orifices of said passage and of said

outlet, a piston valve normally seated in the lower compartment, a stem extending through an opening in said horizontal partition and connecting said piston and said piston valve, and means carried by said stem and engaging with said slideable guide plate for moving the latter into open position when said piston valve has been moved downwardly in the lower compartment a certain distance. 15 20

BYRON L. HANSON.
